(Model.)

L. M. BERRY.

STEAM INJECTOR.

No. 378,281.

Patented Feb. 21, 1888.

UNITED STATES PATENT OFFICE.

LOUIS M. BERRY, OF READING, PENNSYLVANIA.

STEAM-INJECTOR.

SPECIFICATION forming part of Letters Patent No. 378,281, dated February 21, 1888.

Application filed December 1, 1887. Serial No. 256,618. (Model.)

To all whom it may concern:

Be it known that I, LOUIS M. BERRY, a citizen of the United States of America, residing at Reading, in the county of Berks and State 5 of Pennsylvania, have invented certain new and useful Improvements in Steam-Injectors, of which the following is a specification, reference being had therein to the accompanying drawings.

10 This invention pertains to certain new and useful improvements in steam-injectors.

The object of the invention is the provision of an automatic injector with an apertured cylinder or jacket connecting the steam-inlet 15 tube and the lifting-tube, water being drawn in through said cylinder or jacket; also, a combining-tube having apertures opening into an overflow-chamber, whereby the starting of the injector is easily and readily effected.

20 The invention also consists in an improved overflow valve and pipe or chamber by means of which the operator can readily ascertain how the injector is working, and also provide means for the escape of steam when the over- 25 flow is choked.

To these ends the invention comprises the detail construction, combination, and arrangement of parts, substantially as hereinafter fully set forth, and particularly pointed out in 30 the claims.

In the accompanying drawings, Figure 1 is a longitudinal sectional view of my improved steam-injector. Fig. 2 is a vertical sectional view taken through the overflow-chamber, and 35 Fig. 3 is a detail perspective view of the apertured cylinder or jacket.

Referring to the drawings, A indicates the casting or tubular casing, provided at one end with a threaded extension, a, and in its upper 40 surface with a steam-inlet, a', to which is connected, by means of a separable screw-threaded pipe-section, the steam-pipe, (not shown,) while from the under side of the casting or casing is a branch, a², to which is likewise connected the pipe leading from the well or supply of water, the inner end of said branch being curved, as shown. The delivery end a³ is also provided with a pipe-section and coupling-nut for connecting the pipe leading to the 45 boiler.

The casting or casing A is interiorly divided into three compartments, the steam-inlet chamber 2, the water-inlet chamber 3, and the over-

flow-chamber 4, and has interior flanges or shoulders, 5, 6.

B is the steam-jet tube, provided with a flanged head fitting against the flange or shoulder 5 and a contracted inner end and central tapering aperture, as shown. Upon a thickened portion of this steam-jet pipe is formed 60 a screw-thread, b. This steam-jet tube is held firmly in position by means of a plug, b', screwed into the end of the casing, and having an apertured cylindrical extension bearing against the outer surface of the flanged end of 65 said tube, as shown.

C is the lifting-tube, having an outer tapering portion, a central aperture, an outer peripheral flange, 7, and a threaded extension, 8. Upon this lifting-tube is also formed, at a 70 point adjoining the peripheral flange, a screw-thread, 9.

To the threaded extension 8 of the lifting-tube is connected one end of a widened cylindrical extension of a combining-tube, D, having a narrow tapering extension, upon which is formed a screw-thread for securing thereto the inner widened portion of the delivery-tube E. Through the combining-tube and delivery-tube there are of course formed narrow 80 passageways, as shown. In the widened cylindrical extension of the combining-tube D are formed two series of holes or apertures, 10, the holes or apertures of one series being formed on a line with the spaces between those of the 85 other series. There are also formed four (more or less) holes or openings e in the widened portion of the delivery-tube, as shown.

F is a cylinder or jacket apertured throughout its length, and provided at the ends with 90 female screw-threads for screwing said ends to the steam-jet B and lifting-tube C, thus completing the union between all of the tubes or jets of my injector and holding the tapered end of the steam-jet tube in close proximity 95 to the bell-like opening of the lifting-tube. It will be seen that the apertured cylinder or jacket F is located within the water-inlet chamber 3, and that the apertured combining-tube is disposed within the overflow-chamber 100 4, the purpose of which arrangement will soon be apparent.

G is the overflow branch or pipe, formed or cast integral with the tubular casing A, the same being located over the overflow-chamber 105 4, and it has an upper cylindrical extension,

g, from the lower end of which lead two chambers or passage-ways, *g'g'*, opening into a lower extension, *g²*, as shown. To the upper cylindrical extension, *g*, is secured a plug, *g³*, having a cylindrical portion extending into said extension, the upper inner wall of which is curved, as shown.

In the upper wall of the overflow-chamber is formed a circular opening, wherein rests a ball-valve, *H*, as shown, the space between the upper portion of said valve and the curved wall of the plug *g³* being equal to the diameter of either one of the chambers *g'*. To the lower extension, *g²*, of this overflow branch is secured the upper end of a funnel-like pipe or chamber, *I*, provided in its upper surface with a series of openings or apertures, *i*, and to the lower end of this funnel-like chamber is connected one end of a pipe for conveying away the overflow.

The operation is as follows: Steam being admitted through the steam-inlet pipe, will pass through the apertures of the cylindrical extension of the plug *b'* into the steam-jet tube *B*, and, passing through the lifting-tube and out through the apertures of the cylindrical extension of the combining-tube, will raise the ball-valve from its seat and pass out through the overflow branch or pipe. Simultaneous with this operation a vacuum is formed in the water-inlet chamber, which will effect the raising of the water into said chamber, from which it will pass through the apertures of the cylinder or jacket *F*, and, together with the steam, will pass into the combining-tube, and at first a portion will pass out through the apertures of the cylindrical extension thereof on into the overflow, and steam and water will pass through the delivery-tube on into the boiler, any water remaining in the overflow-chamber being drawn through the apertures of the extensions of the combining and delivery tubes. When the steam or steam and water passed from the overflow-chamber, the ball-valve was raised from its seat its full extent, equal, as before stated, to the diameter of the chamber or passage-ways, and said overflow passed on through the funnel-like pipe or chamber into the pipe connected thereto. The object of the funnel-like pipe or chamber is twofold: first, to permit the operator to ascertain by looking through the apertures thereof whether or not any water is passing out with the overflow-steam, and, secondly, when the overflow-pipe becomes choked, causing the backing of the steam and the seating of the valve, said steam is permitted to escape through the apertures in said funnel-like pipe or chamber, thus not only preventing any interference with but providing for the uniformity of the working of the injector. It will be seen that by removing the end plug, *b'*, the entire series of tubes from the steam-jet to the delivery-tube, inclusive, can be removed from the casing, the flanges or shoulders of said casing not interfering with the removal thereof. This is a decided ad-

vantage in this class of inventions, because it is often desirable to remove all the tubes at one time for replacement of any of the worn parts.

From what has been said it will be seen that I have produced an automatic injector extremely simple in construction, one comprising means for effecting a ready and easy starting, one having a highly-efficient overflow located directly over the apertured extension of the combining-tube, and one having an apertured funnel-like overflow pipe or chamber, which is a decided improvement in the art.

I claim as my invention—

1. As an improvement in steam-injectors, the overflow branch or pipe comprising two channels or passage-ways and an upper cylindrical extension, and the ball-valve located in said cylindrical extension and having a movement about equal to the diameter of said channels or passage-ways, substantially as shown and described.

2. The overflow branch or pipe having two channels or passage-ways, the ball-valve, and the funnel-like pipe or chamber having a series of apertures, substantially as shown and described.

3. As an improvement in injectors, the funnel-like pipe or chamber secured to the overflow branch or pipe and having a series of apertures, as shown, and for the purpose stated.

4. In a steam-injector, the combination, with the casting or casing having an aperture in its upper portion, of the overflow branch or pipe having two channels or passage-ways and upper and lower cylindrical extensions, the plug screwed in the upper one of said extensions and having an inner curved wall, and the ball-valve normally resting on said aperture of the casing and having a limited movement in said upper extension, substantially as shown and described.

5. The combination, with the casing, of the end plug having a threaded portion fitting a corresponding thread of said casing and an apertured extension, the steam-inlet jet-tube held by said plug and provided with a thread, the lifting and combining tubes, and the apertured cylinder or jacket secured to said steam-inlet jet-tube and to said lifting-tube, substantially as shown and described, said lifting-tube and cylinder or jacket and combining-tube being screwed together, as stated.

6. The herein-described improved injector, comprising the steam-inlet jet-tube, the apertured cylinder or jacket, the lifting, combining, and delivery tubes, the overflow branch or pipe having two channels or passage-ways, the ball-valve, and the funnel-like pipe, all constructed and arranged substantially as shown and described.

In testimony whereof I affix my signature in presence of two witnesses.

LOUIS M. BERRY.
